CAP MECHANISM FOR TREATING FELLED GREEN TIMBER

Myron M. Clapshaw, Portland, Oreg., assignor, by mesne assignments to Mineralized Cell Wood Preserving Company, Seattle, Wash., a corporation of Delaware

Application April 11, 1934, Serial No. 720,111

7 Claims. (Cl. 21—71).

My invention relates to a cap mechanism for treating felled green timber containing its natural sap. More particularly, my invention relates to a cap adapted to be applied to the butt end of the felled green timber containing its natural sap, which timber may be of varying diameter, and which cap is connected to a reservoir of chemicals under pressure, so that the chemicals may be forced through the longitudinally directed ducts of the said timber.

The tendency to decay in the case of telegraph poles, pilings, ties, and in fact all wood units which come in contact with the elements, such as soil, water, or air, or any combination thereof, or are exposed to the action of termites, teredoines and other wood destroying insects or borers, is well known. The replacement cost is tremendous, besides the unnecessarily premature destruction of an important natural resource is involved. Accordingly, many attempts have been heretofore made to overcome this objection, all of which involve expensive operations and expensive treating plants and expensive transportation due to reshipment of the timbers after treatment.

Heretofore many cap devices have been suggested as the means secured to the end of the log in which means the treating solution to be forced into the log is subjected to pressure to pass the treating solution through the sap and portion of the timber longitudinally of the cell structure, but when it is attempted to apply them to commercial use, it is found that they embody serious objections which make them impossible of use.

When made of iron they are subject to attack by the chemicals forming the treating solution and metal walls cannot be readily forced into liquid tight seal bearing on the pole without beveling off the end of the pole and thereby blocking off part of the sap wood portion of the pole from treatment. Particularly does this result when the metal cap is of truncated cone form which form is employed to adapt the cap to be applied to poles of varying diameters.

Air pockets must be avoided and when air venting means is suggested in the prior art devices, they are with difficulty separately adjustable to poles of a given diameter, which renders the operation too costly due to the time consumed.

On the other hand when material as rubber is proposed to overcome the chemical effect of the treating solution and the rubber cap of the required elasticity to fit varying diameters of poles

is shown of the design heretofore suggested, the cap lacks strength to sustain the pressure which becomes more than fifteen hundred pounds on a pole of 18 inch diameter with a 7 pound pressure per square inch.

Also when a rubber cap is formed of vulcanized fabric and rubber, the means heretofore designed for clamping it upon the pole which may have its bark on involves puckering when it is cinched so that a liquid tight seal is not obtained. And even when the cap is applied to a peeled pole, the surface is uneven and the same objection develops as set forth immediately above.

Primary purposes of my invention are to provide a cap apparatus by means of which to carry out the process for treating felled green timber with chemicals at or near the site where the same is cut and then shipped direct to the point of use. And which cap means overcomes the objections above mentioned.

This application is a continuation-in-part of application bearing Serial No. 673,415, for "Process of preserving green timber, etc."

For purposes of definiteness and illustration I will describe my invention as applied to the treatment of poles, piling, ties and other wood articles, or to such timbers from which said ties or lumber or veneer are to be cut, where the use of such products requires non-water absorbing or non-decaying properties, or to be resistant to marine boring animals or to termites or wood destroying insects, or where it is desirable to prohibit excessive season checking and other troubles which arise in dry kilning. In treating green felled timber in accordance with the process above identified, it is important that every part of the sap wood structure be treated, i. e., so no part is left untreated. This requires the careful elimination of all air pockets developing in the cap apparatus. Also it requires an apparatus which may be adjusted to the ends of timbers of varying diameters. Furthermore, such apparatus must be of a light weight but strong construction as it must sustain high pressures and it must be capable of being handled readily by the operators to avoid delay in attaching the same to the poles for treating. Furthermore, it is important that the cap be of a flexible elastic character to partially absorb the pulsations incident to the pumping operation by means of

which the chemicals in solution are forced through the longitudinal ducts of the timber. This avoids undue strain upon the pump and provides for maintaining a constant pressure on the fluid, whereby the treating of the pole is

facilitated. And only a steady flow and pressure is maintained on the cell walls such as to prevent reaction between the treating solution and the sap in fact or in the presence of the sap. The above mentioned general objects of my invention, together with others inherent in the same, are attained by the device illustrated in the following drawings, the same being preferred exemplary forms of embodiment of my invention, throughout which drawings like reference numerals indicate like parts:

Fig. 1 is a view in side elevation of the end portion of a pole and an apparatus attached thereto for impregnating the said pole with the preserving solution;

Fig. 2 is a view in longitudinal section of

Fig. 1;

Fig. 3 is a view in longitudinal section of the pole with bark removed to form a bearing for the cap;

Fig. 16 is a view in perspective of a modified form of the tightening member for the cable, i. e. cap engaging means;

Fig. 17 is a view of a modified form of cap engaging means; and

Fig. 18 is a view in cross-section on dotted line 18-18.

In causing the reaction of the solution with the sap of the felled green timber, the apparatus shown in the drawings is efficient and practical, and provides for a thorough and uniform treatment of the timber. The cap 3 is secured to the end of the pole 4. The end of the pole is partially trimmed to form a more or less smooth or uniform bearing portion 5 for the cap. In providing this bearing 5 it is preferable to leave a part of the bark upon the pole and not strip it to the wood structure entirely. This provides for a thorough impregnation of the chemicals throughout the portion of the pole treated up to the bark. An extra supply of chemicals may locate between the bark and the woody structure. This is particularly advantageous where the pole is to be used as a piling with the bark left on. There is no necessity for beveling off the annular edge of the pole, and particularly do I not

want to cut the sap wood. The form of the cap of my invention is such as to provide for fitting upon poles of varying diameters without such cutting, and at the same time of a form to prevent air cutting off access of the liquid to the sap wood disposed to the upper part of the butt end of the pole, as well of a rubber fabric material which is non-reacting with the treating solution and flexible so as to be secured with a liquid tight seal to the pole.

The cap is of a form having practically a 90° angle 6 between the side 7 and the end wall 8, while the angle 9, i. e., the angle between the end wall 8 and the side 10 is preferably obtuse. In longitudinal section the cap has substantially the form of a truncated cone, having the top side perpendicular to the plane of the ends. That portion of the cap which is attached to the log is herein termed the base portion, while the opposite end portion is called the top portion. That part of the cap which is substantially in line with the top of the log lying in general in a horizontal position is referred to herein as the upper portion of the cap. The cap may be secured in position on the end of the pole by means of a wire cable or other similar means 11, the ends of which are secured by a cable tightening means 12. Also a further securing means may be employed in the form of a U shaped member 13 having spears or dogs 14 which may be driven into the timber to insure the fast securing of the cap to the end portion of the pole when the solution in the cap is subjected to pressure. It will be understood that the continued pumping of the fluid to the cap creates a vibration that will gradually work the securing means loose so that it is not liquid tight unless particularly efficient securing means are provided.

An air escape valve 15 is provided in the upper wall portion of the cap so that air pockets will not form and prevent the chemical solution from having full and free access to the sap wood part of the log in the upper part of the log. Also an inlet conduit 16, which has valve 17, is attached to the lower part of the top portion of the cap so as to serve also as a means for draining off the unused chemicals down to the level of said inlet conduit when the treating is completed. The remaining liquids may be readily caught in a vessel upon loosening the securing means 12. The conduit 16 connects with any suitable confined receptacle in which the treating solution is contained, and to which said solution fluid pressure may be applied. Upon opening the valve 17 the solution runs into the cap 3 and any confined air is then permitted to escape through valve 15 so that the cap 3 is completely filled with the treating solution. When the cap 3 is completely filled with the treating solution the air venting valve 15 is closed. During the treating period as the solution is pumped or otherwise supplied under pressure to the cap, air collects and the venting of the air must be repeated from time to time to positively avoid allowing a pocket of air to form. The fluid pressure exerted upon the treating solution is preferably between 5 and 25 lbs. The magnitude of the pressure obviously depends upon the density of the particular wood being treated and the length of the said poles to be treated.

In Fig. 4, a modified form of a cap securing means, with parts broken away, is illustrated as applied to a log. This is preferred to the form shown as element 12 in Fig. 1. The wire cable 11 becomes very much kinked by the clamping

means there shown, and when severely kinked it is difficult to employ it to bind the base of the cap to the log with a liquid tight seal. In the modified form, an arc-shaped plate 18 longitudinally considered is shown having a flange 19 with a claw member 20 disposed with rod 21 extending through opening 22 in the flange 19, so that a nut 23 may be employed to draw clamp member 20 toward the flange. Claw member 20 has a transversely directed plate 24, see Fig. 5, and a pin 25 disposed to slide in a slot 26 in plate 18. At the opposite end of the plate 18 there is a clamping plate 27 having a groove 28 and bolt holes 29. A cap engaging means as a wire cable 30 is provided with an enlarged end portion 31 which is disposed within the claws of the claw member 20. The round surface of the cable provides an enlarged bearing surface in cinching the cable to the depressible cap walls. In being applied the cable is then placed around the base portion of the cap in position on the log 4 and beneath the flange 19 and through groove 28. Then bolts 31 are drawn tight so that the cable 30 is clamped tight against the plate 18. Thereupon the cable is drawn to a very tight fit upon the cap by applying a wrench to nut 23 and drawing forwardly the claw member 20. The plate 24, together with pin 25, operates to keep the claw member 20 from turning axially. The plate 24 has a bearing against the underside of substantially the entire width of the plate 18.

In place of driving dogs 14 into the log as shown in Fig. 1, to provide an anchoring means for the cap 3, it is preferable not to rupture the bark and the wood structure therebeneath, because all such openings permit the escape of the treating solution. To avoid this, varying types of anchoring means are provided, such as are illustrated in Figs. 8 and 9. In Fig. 8 an anchoring chain 32 is provided with a cinching means in the form of a lever 33, in one end of which is a hook 34. A tightening member 35 may be pivotally secured to lever 33. A plate 36 having a flange 37, through a hole 38 in which flange member 35 is caused to extend, having nut 39. At spaced intervals on chain 32, are short chain lengths 40. The anchoring chain 32 is placed around the log some 18 inches or two feet from the base of the cap 3. Thereupon lever 33 is forced back and secured down by hook 41 to chain 32. Member 35 with nut 39 provides for further tightening adjustment if necessary. In general the position of such an anchoring means, with respect to the cap, is shown in Fig. 14. A somewhat similar chain anchoring means is shown in Fig. 9. The lever 33 is omitted here and a hook 42 with an upturned flange 43 is provided with an opening 44 through which pin or tightening member 45 extends, which likewise passes through a flanged plate 46. Nut 47 serves as an adjusting means to draw plate 46 towards hook 42. The plate 46 is secured to an anchoring chain 48, which chain has, at spaced intervals, short laterally disposed chain members 49 with hooks 50.

In Fig. 10 is illustrated a blank 51 for forming the body portion of the cap 3 on the mold member 52 shown in Fig. 12. This blank consists of a fabric with rubber coating on both sides of a thickness to provide movement with respect to the superimposed fabric plate. Overlapping portions 53 and 54 are provided on each end of the blank 51 to provide the joint.

In Fig. 11 a cap blank 55 is shown to form the

end wall 8 of the cap. Notches 56 enable the peripheral portion 57 of the blank 55 to extend over the blank 51, forming the body portion, as will be readily understood.

The blanks 51 are placed upon the mold 52, and the edges 53 and 54 are caused to overlap, and then a second blank, exactly like 51, is added, however with the joint placed at a 120° position with respect to the first joint, and a third blank 51 is added with its joint spaced 240° from the first joint. After the adding of each of the above joints, the cap 55 is added and the notches 56 are placed in staggered relation with respect to the notches of underlying blanks 55, so that the notches or joints are not directly superimposed. The assembly is then vulcanized into a unit, leaving "live" rubber between the fabric members. Since at the joints there is manifestly a double thickness of the rubber and between each fabric member there is rubber, it results that there is more or less elasticity provided in the finished cap and the cap walls as a whole are flexible. This provides for cinching the cap walls to the uneven surface of the pole bark or pole with a substantial bearing and a liquid tight seal.

In Fig. 13 a modified form of cap is shown. In this instance a cap body 58 is provided of relatively high elastic rubber, so that the base portion may be adjusted to the butt ends of poles of different diameter by merely stretching the base 59 and a fluid inlet conduit 60. A cap securing means in the form of a cable, preferably wire is shown at 61. This may be of the type of cable 30, with associated clamping plate 13 and its various members as illustrated in Fig. 4. Manifestly, a cable of hemp may be used for means 61, and may be drawn very tight by being wetted after being placed in position on the cap.

Over the cap body 58 is placed a reinforcing cap 62 (Fig. 14) of relatively non-elastic material. This reinforcing cap is provided with lacing means 63 so as to adjust the said cap to fit properly over cap 48, the fitting being preferable on account of cap 58 being adjustable to logs of different diameters. An opening 64 is provided for conduit 60. Straps 65 with cinch buckles 66 and hooks 67 are provided to secure cap 62 to anchoring means 68, which may be of a suitable type, such, as for example, as is shown in Figs. 8 and 9.

In Fig. 15 the plan view is shown of the end portions of the cap engaging means of Fig. 4 which lie side by side or in overlapping relation but however, not necessarily crossing over each other.

In Fig. 16, is shown a modified form of tightening means 69 which has flanges 70 to engage the lateral edges of plate 18 and has hook 71 in place of a claw as member 20.

In Fig. 17, a modified form of cap engaging means in the form of a band 72 of spring metal with a raised portion 73 (Fig. 18) which raised portion assists in establishing a liquid tight contact between the cap and the timber.

Obviously, in general changes may be made in the forms, dimensions and arrangements of the parts of my invention, unless the context indicates otherwise, without departing from the principle thereof, the above setting forth only preferred forms of embodiment.

I claim:

1. A device of the character described, embodying a flexible pole treating cap formed of fabric reinforced rubber walls, said cap having

1 a pliable circumferential edge portion conformable under a binding cable with the uneven circumferential bearing of exposed sap wood of a felled tree to form a liquid tight seal and a cap securing means having a cap engaging means, a 5 securing plate, the end portions of said cap engaging means overlapping directly beneath said plate over an arc of such length as to bring the secured ends substantially beneath the line tangent at the point in about the middle of the arc 10 beneath the point of said cap engaging means.

15 2. A device of the character described, embodying a cap formed of flexible, elastic vulcanized wall, said cap being of truncated cone form in longitudinal section, said form rendering the base portion capable of being fitted to logs of varying diameters, the upper wall portion of said cap being substantially in line with the upper portion of the log; and an air escape valve disposed in said upper wall portion in the end portion 20 of the cap removed from the log.

25 3. In a device of the character described, a pole cap securing means comprising a cap engaging means; an arc shaped plate having at one end a cap engaging means tightening member, and on the other end, a clamping means for one end of said cap engaging means, said arc shaped plate being of such length as to cause the end portions of the cap engaging means to lie side 30 by side and to cause the secured ends of the cap engaging means to lie positioned substantially beneath the line tangent to about the middle point of the arc beneath the point of said cap engaging means.

35 4. In a device of the character described, a pole cap securing means comprising a cap engaging means; an arc shaped plate having a flange on one end with a hole therethrough, and a longitudinally directed slot in said plate; a cap 40 engaging means tightening member having a pin operatively positioned in said slot and a claw member on one end and a threaded portion on

one end, which threaded portion extends through and in operative engagement with the walls of the hole in said flange; and a cap engaging means clamping plate and means to secure said plate to the end of said arc shaped plate opposite to the 5 flange end of said arc shaped plate, said plate being of such length as to cause the end portions of the cap engaging means to lie side by side and to cause the secured ends of the cap engaging means to lie positioned substantially beneath the 10 line tangent to about the middle point of the arc beneath the point of said cap engaging means.

15 5. In a device of the character described, a pole treating cap formed of a plurality of superimposed fabric blanks having vulcanized rubber 15 coated faces, the said rubber coating being elastic to permit movement of one blank with respect to the other.

20 6. A device of the character described, comprising a pole treating cap formed of live rubber 20 of high elasticity and pliability, whereby said cap is conformable under a binding cable with the uneven circumferential bearing of the exposed sap wood of the felled tree to form a liquid 25 tight seal; an air escape valve disposed in the upper wall portion thereof; means to secure said cap upon the pole; and a reinforcing cap of flexible non-elastic material disposed over said pole 30 treating cap.

35 7. A device of the character described, comprising a pole treating cap formed of live rubber 35 of high elasticity and pliability, whereby said cap is conformable under a binding cable with the uneven circumferential bearing of the exposed sap wood of the felled tree to form a liquid tight 40 seal; an air escape valve disposed in the upper wall portion thereof; means to secure said cap upon the pole; and a reinforcing laced cap of flexible non-elastic material disposed over said pole treating cap.

40 MYRON M. CLAPSHAW.
